UNITED STATES PATENT OFFICE

ISAAC S. DRAPER, OF SULLIVAN, INDIANA

HEADLIGHT ANTI-GLARE DEVICE

Application filed July 23, 1928. Serial No. 294,811.

The invention relates to anti-glare devices for automobile headlights and analogous illuminators, and it aims to provide a simple and inexpensive, yet an efficient and reliable article of this character which may be quickly and easily installed and adjusted to obtain the best results, and will not interfere with replacing bulbs whenever necessary.

With the foregoing in view, the invention resides in the novel subject matter hereinafter described and claimed, description being accomplished by reference to the accompanying drawing.

Fig. 1 is a side elevation partly in section showing the device applied.

Fig. 2 is a side elevation of the anti-glare device separate from the head-light.

Fig. 3 is a vertical sectional view on the correspondingly numbered line of Fig. 2.

In the drawing above briefly described, the preferred details of construction have been illustrated and while these details will be herein specifically explained, it is to be understood that within the scope of the invention as claimed, minor variations may be made.

The device embodies a flat metal disk 5 having a central opening 6 to receive the usual neck 7 of a headlight bulb 8. The front side of this disk is provided with a light-reflecting surface 9, and a plurality of slots 10 are formed through said disk around the opening 6 to expose portions of the reflector 11 behind said disk, providing for the necessary direct forward projection of light rays. The slots 10 are elongated in directions at right angles to lines radiating from the center of the opening 6.

Integral with the peripheral edge of the disk 5 are a number of circumferentially spaced fingers 12 which are greater in number than the slots 10 and project forwardly to surround the bulb 8, said fingers being of a length to project forwardly beyond the foremost part of the bulb a distance approximating one-third the length of said fingers. The

fingers are also diametrically spaced a distance greater than the diameter of the glass part of the bulb so as to be spaced in their entirety from the latter. In transverse section, these fingers are straight as seen in Fig. 3. Longitudinally however, they are curved, the rear portions of said fingers being bowed outwardly away from the glass part of the bulb 8 while the front portions of said fingers are inwardly bowed. These fingers are readily bendable so that they may be adjusted according to the size of the bulb or the shape of the reflector 11 to obtain the best results, and as they are of thin sheet metal, their front ends may readily be cut off or bent back should this be necessary to clear the usual lens. The outer sides 13 of the fingers 12 are enameled or otherwise provided with a dark coating of light-mellowing nature, dark green enamel being preferably employed. The inner sides 14 of these fingers however are enameled or otherwise coated with a light color such as white or cream, so that they do not materially reduce the strength of the light rays, yet will not forcibly reflect such rays with danger of temporarily blinding persons looking toward the light.

For holding the device in proper position upon the bulb neck 7, I prefer to use a light coil spring 15 soldered or otherwise secured to the rear side of the disk 9. When the device is applied, this spring is held under compression and it consequently holds the disk and fingers in proper position and prevents rattling of them.

When the device is properly applied and adjusted, it effectively prevents danger of glare from headlights and analogous illuminators, yet sufficient illumination is given for safe driving. The coloring of the inner and outer sides of the fingers 12 is of importance, the light color on the inside and the dark green on the outside, serving to effectively break the glare of the light with much bet-

ter results than when using any other colors, all of which have been tried. The reflecting surface 9, such as nickel-plating, together with the portions of the headlight reflector exposed through the slots 10 serve to direct reflected light rays where needed and yet avoid dangerous glare, co-operating with the other features of construction in producing a highly desirable and efficient device, regardless of its simplicity and ease of application. Any time it is necessary to install a new bulb, the anti-glare device will not interfere to any extent with such installation, and as above stated, this device may be adjusted by bending the fingers 12 so as to obtain the best results, according to the reflector's shape and the size and shape of the headlight bulb.

I claim:

- 20 1. In combination with a headlight having a reflector and a bulb; a disk having a central opening through which the usual neck of the bulb passes, said disk having a reflecting surface at its front and being provided also with openings exposing portions of the reflector behind said disk, means for holding said disk upon the bulb neck, and a plurality of circumferentially spaced reflector shielding fingers integral with the peripheral edge of the disk and projecting forwardly therefrom around the bulb, said fingers being of a length greater than the usual glass portion of the bulb and projecting forwardly beyond the foremost part of the latter, said fingers 25 being diametrically spaced a distance greater than the diameter of said glass portion of the bulb and being hence outwardly spaced in their entirety from said glass portion, the outer sides of said fingers being 30 provided with a dark light-mellowing coating, the inner sides of said fingers having a coating of light color which will not materially reduce the light volume but will prevent reflection of glaring rays.
- 45 2. In combination with a headlight having a reflector and a bulb; a flat disk having a central opening through which the usual neck of the bulb passes, said disk having a reflecting surface at its front and being provided also with slots elongated transversely of radial lines, said slots exposing portions of the reflector behind said disk, means for holding said disk upon the bulb neck, and a plurality of circumferentially spaced reflector shielding fingers greater in number than said slots, said fingers being integral with the peripheral edge of the disk and projecting forwardly therefrom around the bulb, said fingers being of a length greater than the glass portion of the bulb and projecting forwardly beyond the foremost part of the latter, said fingers being diametrically spaced a distance greater than the diameter of said glass portion of the bulb and being hence 50 outwardly spaced in their entirety from said

glass portion, the outer sides of said fingers being provided with a dark light-mellowing coating, the inner sides of said fingers having a coating of light color which will not materially reduce the light volume but will prevent reflection of glaring rays, said fingers being straight in transverse section, having their rear portions bowed outwardly and having their front portions similarly bowed inwardly.

In testimony whereof I have hereunto affixed my signature.

ISAAC S. DRAPER.
